UNITED STATES PATENT OFFICE.

ALFRED A. WELLS, OF MONTCLAIR, NEW JERSEY, ASSIGNEE TO ELLIS-FOSTER COMPANY, A CORPORATION OF NEW JERSEY.

CRACKING OIL.

1,187,874.

Specification of Letters Patent. Patented June 20, 1916.

Application filed November 17, 1915. Serial No. 61,901.

To all whom it may concern:

Be it known that I, ALFRED A. WELLS, a citizen of the United States, and a resident of Montclair, in the county of Essex and 5 State of New Jersey, have invented certain new and useful Improvements in Cracking Oil, of which the following is a specification.

This invention relates to a method of making gasoline from heavier oils and 10 relates in particular to the decomposition of oil in a bath of molten metal such as molten lead, whereby light products are formed.

It has been proposed to mix molten lead and oil as a spray which is passed over 15 refractory material but such operation requires the use of a large amount of power and has other disadvantages. In the present 20 method the oil or oil vapors are passed through a bath of molten metal which is preferably maintained in agitation by 25 mechanical stirrers, such stirrers being preferably arranged so as to vigorously agitate the oil or vapors just on entry into the lead bath in order to prevent the formation of large 30 particles of coke or coarse masses of tar and the like which cause difficulties in the operation of the apparatus. Preferably the lead or the metal bath is also agitated at a point more remote from the seat of entry of the

oil or oil vapors.

In order to maintain the temperature of the metal bath external heat may be applied but this has the disadvantage of rendering the outer portions of the bath too high in

35 temperature so that superheating occurs with the formation of coke and the like on the surface of the iron or other container which prevents the proper transmission of heat and also leads to carbonization with

40 weakening of the metal walls of the container. By the present process, the heating

is preferably applied internally by means of a burner, situated within the lead bath, of a character such that should the walls of the

45 heating appliance give way dangerous results would not occur. In the preferred form the heating appliance is of the surface combustion type and a mixture of oil vapors or gases resulting from the cracking operation or other suitable fuel is mixed with

50 air and forced into a mass of refractory granular material contained in a tubular heating device situated in the metal bath. Preferably the waste gases from the crack-

55 ing operation are used so that the whole ap-

paratus operates as a unit and the residual gases which otherwise would be used more or less ineffectively or allowed to go to waste are employed usefully in the present process.

Almost any type of petroleum oil may be treated in this apparatus in accordance with the present process but preferably I use kerosene or similar oil which may be fed into the apparatus without first vaporizing and the vaporization may be allowed to occur in the lower part of the apparatus but preferably the oil is not only vaporized but is somewhat preheated to a point below the cracking point before it enters the metal bath. The temperature of the bath may be about 900-1000° F. but the temperature varies with the oil which is being treated. In the decomposition which takes place in the latter, carbon is formed which floats to the surface and is either blown out of the apparatus or removed from the top of the bath. The particles carried over in the vapors are largely caught in a dust collector in which the sulfid of lead is also collected when sulfur is present in the oil. The use of oils containing high percentages of sulfur is feasible with this apparatus as the sulfur is taken out quite effectively and the sulfid of lead may be collected and treated to recover the metal. Sulfur-containing Mexican or California oils may thus be used to advantage.

In the drawings Figure 1 shows in vertical section and elevation an organization capable of carrying out the process herein described, while Fig. 2 shows in elevation a modified form thereof.

Like reference characters denote like parts throughout the drawings.

In the drawings 1 is a closed receiver having heat insulating jacket 2. It is partly filled with a bath of molten metal such as lead shown at 3. The receptacle is equipped with a stirrer 4 having a small mixing propeller 5 and a large stirring propeller 6. 7 is a driving pulley. In the bath of molten lead is the heating element 8 which has a tube carrying fragments of fire brick or other refractory material.

9 is the fuel pipe forming a part of the heating element which has a gas supply pipe 10 and air supply pipe 11 equipped respectively with pumps 12 and 13. The pipe 9 passes around or to one side of the lower

propeller and does not interfere with the movement of the latter.

14 is a thimble of refractory material having an opening for the air and gas mixture which is proportioned with respect to the rate of flow of the explosive mixture employed, so as to bring about combustion in the refractory material contained in the tube 8 without danger of back firing.

10 15 is an outlet for the exhaust gases which may be by-passed by pipe 16 through the heating coil 17 contained in the preheating tank 18. The feed pipe 19 is equipped with pump 20 which is arranged to force oil 15 through the orifice 21, into the bath of molten lead.

22 is an outlet pipe for the gas and vapors.

23 is a dust chamber and carbon collector.

24 is a pipe connecting 23 with the condenser 25. The condenser has an outlet pipe 20 at the bottom equipped with trap 26 from which the condensed material is carried to the receiver 27.

28 is an exhaust pipe for the gases and 25 29 a pump to force these through a scrubbing tower 30.

31 is a pipe leading to the pump 12 conveying the residue gases to the furnace.

31^a is a supply pipe for additional fuel 30 gas if required.

In Fig. 2, 1 is the receptacle containing molten metal, 4 is a stirrer which is hollow and which has outlets 35 and 36. Thus the oil is brought into the body of metal 35 but out of contact with it until at or near the lower part of such metal body when the oil or vapors thereof as the case may be are released or liberated in contact with the metal material and are agitated during contact with the metal. This stirrer is rotated 40 by gear work 33. 34 is a pump to force oil into the hollow stirrer. 32 is an ordinary furnace.

What I claim is:—

45 1. The process of cracking oils which consists in passing the oil vapors into a bath

of molten lead at about 900-1000° F. maintained in a state of agitation by mechanical agitating means and in violently agitating the vapors substantially at the moment of 50 contact with the molten bath.

2. The process of cracking oils which consists in passing the oil vapors into a bath of molten lead maintained in a state of agitation by mechanical agitating means and in 55 violently agitating the vapors on contact with the molten bath.

3. The process of cracking oil which consists in passing oil vapors containing sulfur into a bath of metal heated to a decomposing temperature, in collecting the gases arising from the cracking operation, in returning these to the metal bath and burning same within the bath; whereby the heat required for the cracking operation is 60 in part at least supplied by the vapors of the oil undergoing the cracking treatment.

4. The process of cracking a petroleum oil which consists in passing said oil into a bath of molten lead heated to about 900- 70 1000° F., and maintained in a state of agitation by mechanical agitating means and in violently agitating the vapors at the moment of contact with the molten bath.

5. The process of making gasoline by 75 cracking a heavier oil which consists in passing petroleum oil into a bath of molten metal heated to at least a cracking temperature and maintained in a state of agitation by mechanical agitating means and in violently agitating with the vapors at the moment of contact with the molten bath.

6. The process of cracking a heavier oil into a lighter oil which consists in passing such heavier oil into a bath of molten lead 85 heated to at least a cracking temperature and maintained in a state of agitation by mechanical agitating means and in violently agitating the vapors of said oil during the period of contact with the molten bath.

ALFRED A. WELLS.
